UNITED STATES PATENT OFFICE

JAMES C. WYNDER, OF HARTSVILLE, SOUTH CAROLINA, ASSIGNEE TO SONOCO PRODUCTS COMPANY, OF HARTSVILLE, SOUTH CAROLINA, A CORPORATION OF SOUTH CAROLINA

WINDING DEVICE

Application filed November 7, 1930. Serial No. 494,095.

This invention relates to spools, reels, bobbins, or like winding devices and more particularly to securing means for fastening end discs or flanges to the body members of such devices.

The principal object of the invention is to provide an improved spool or the like, the end discs of which are secured to the body member by means of novel fastening elements which are exceedingly light in weight, inexpensive and simple in construction, and well adapted to rigidly unite spool members to effectively prevent relative movement therebetween.

Other objects and features of novelty will be apparent from the following specification when read in connection with the accompanying drawing in which one embodiment of the invention is illustrated by way of example.

In the drawing,

Figure 1 is an elevational view of a spool embodying the principles of my invention; one end of the spool being shown in vertical cross-section to illustrate the end flange securing means;

Figure 2 is an end view of the spool; and

Figure 3 is a perspective view of one of the fastening elements employed.

In Figure 1 of the drawing, there is illustrated at 10 an example of the type of spool or winding device which embodies the principles of the present invention. The spool 10 is seen to consist of a body member or barrel 11 which may be tubular or solidly constructed with openings or recesses at the ends thereof. In the form shown in the drawing, the bore or opening of the body member is designated by the numeral 12. End discs 13 provided with central apertures 14 are positioned at the ends of the body member 11 with the apertures 14 and the opening 12 in substantial registry.

The essential part of the securing means employed for fastening the discs 13 to the

body members 11 comprises the element 15 which is clearly shown in perspective in Figure 3 of the drawing. The element 15 is constructed of a strand or filament which may be a cord, thread, or similar fibrous material but is preferably formed of wire. In the fabrication of the element 15 a continuous length of such filamentous material is bent to form the spaced convolutions which comprise vertical portions 16 in the position shown in Figures 1 and 3 and the horizontal portions 17. The upper portions of the convolutions are bent at right angles to the original plane of the convolutions and the ends of the element are brought together so that the whole device forms a skeletonized or reticulated cylinder 18 having an outer flange 19 formed thereon. The completed securing element 15, as shown in Figure 3, is then inserted in the end of the assembled spool so that the cylindrical part 18 formed by the convolutions of the wire lies against the wall of the opening 12 and the skeleton flange 19 formed by the outwardly bent portions of the convolutions is adapted to overlie the margin of the aperture 14 of the end disc 13. A plug or bushing 20 which is preferably formed with a slight taper 21 at its inner end and with a bore 22 to provide a bearing for an axle, is then forced into the end of the spool. The diameter of the greater portion of the plug or bushing 20 is substantially the same as the diameter of the opening 12. Thus it will be seen that the convolutions of the securing element 15 are embedded in the material forming the wall of the opening 12. As the plug or bushing 20 is driven home so that its outer surface occupies substantially the same plane as the outer surface of the end disc 13, those portions of the convolutions which form the flange 19 are struck or pressed with a suitable tool and are firmly embedded in said outer surface of disc 13 around the margin of the perforation 14.

Both the body member or barrel 11 of the

spool and the end discs 13 must be made of some rigid material which is, however, soft enough to permit penetration of the fastening element therein. The bushing 20 may be formed of metal or any other like material but is preferably constructed of wood or fiber so that the fastening element 15 may be embedded to some extent therein as well as in the wall of the opening 12 and the end disc 13, thus effectively preventing relative movement not only of the end disc 13 and the body member 11 but also of the bushing 20 and said body member.

It is conceivable that the filamentous material employed in the construction of the securing elements 15 may be of thread, cord, or other fibrous material (instead of wire as in the preferred form), through the use of a suitable adhesive substance which will cause the convolutions of the element to firmly adhere to the walls of the opening 12, the disc 13 and the plug 20 in the absence of the relative stiffness or rigidity of the securing element as formed of wire. It will be understood that the terms "wire", "filament", or similar terms, as used in the claims, are meant to cover all reasonably suitable or equivalent substances which may be employed in this connection.

It will thus be seen that by means of the present invention there has been provided an effective securing device for rigidly connecting the end discs or flanges to the body members or barrels of spools, reels and like winding devices, one of the most important features of which is the simplicity and economy of construction of these devices, which will permit them to be manufactured cheaply and in the exceedingly great numbers required by the textile, electrical and numerous other industries.

It is to be understood that various other changes and modifications may be made in the securing elements herein disclosed without departing from the scope of the present invention as defined in the following claims.

Having thus described the invention, what is claimed as new and desired to be secured by Letters Patent is:

1. In a spool, in combination, a body member provided with an opening in the end thereof, an end disc having a central aperture registering with said opening, and means for securing said disc to said body member comprising a piece of wire bent to form convolutions, portions of one or more of which are disposed in contact with the wall of said opening and other portions of which overlie the margin of the aperture in said end disc.

2. In a spool, in combination, a body member provided with an opening in the end thereof, an end disc having a central aperture registering with said opening, and means for securing said disc to said body

member comprising a piece of wire bent to form convolutions, portions of one or more of which are embedded in the wall of said opening and other portions of which are embedded in the margin of the aperture in said end disc.

3. In a spool, in combination, a body member provided with an opening in the end thereof, an end disc having a central aperture registering with said opening, means for securing said disc to said body member comprising a piece of wire bent to form convolutions, portions of one or more of which are disposed in contact with the wall of said opening and other portions of which overlie the margin of the aperture in said end disc, and means for retaining the convolutions of said wire which are disposed within said opening in firm contact with said inner wall.

4. In a spool, in combination, a body member provided with an opening in the end thereof, an end disc having a central aperture registering with said opening, means for securing said disc to said body member comprising a piece of wire bent to form convolutions, portions of one or more of which are disclosed in contact with the wall of said opening and other portions of which overlie the margin of the aperture in said end disc, and a bushing wedgingly inserted in said opening for retaining the convolutions of said wire which are disposed within said opening in firm contact with said wall.

5. In a spool, in combination, a body member provided with an opening in the end thereof, an end disc having a central aperture registering with said opening, means for securing said disc to said body member comprising a piece of wire bent to form convolutions, portions of one or more of which are disclosed in contact with the wall of said opening and other portions of which overlie the margin of the aperture in said end disc, and a bushing wedgingly inserted in said opening for retaining the convolutions of said wire which are disposed within said opening in firm contact with said wall, said wire also being embedded to some extent in the outer wall of said bushing.

6. In a spool, in combination, a body member provided with an opening in the end thereof, an end disc having a central aperture registering with said opening, means for securing said disc to said body member comprising a filament bent to provide a circular series of convolutions, portions of which form a cylinder extending into said opening and are embedded in the wall thereof and other portions of which are flared radially exteriorly of said opening so as to overlie and retain the margin of the aperture of said end disc.

7. In a spool, in combination, a body member provided with an opening in the end thereof, an end disc having a central aper-

ture registering with said opening, means for securing said disc to said body member comprising a filament bent to provide a circular series of convolutions, portions of 5 which form a cylinder extending into said opening and are embedded in the wall thereof and other portions of which are flared radially exteriorly of said opening and are embedded in and retain the margin of the 10 aperture of said end disc, and a plug wedgingly inserted in said opening to retain said convolutions in engagement with the wall of said opening.

15 In testimony whereof I hereunto affix my signature.

JAMES C. WYNDER.
